Primary Examiner — Cynthia M Chin(74) *Attorney, Agent, or Firm* — Nixon & Vanderhye P.C.(57) **CLAIM**

The ornamental design for a riding device, as shown and described.

DESCRIPTION

FIG. 1 is a front perspective view of a riding device showing my new ornamental design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is a rear perspective view thereof.

The broken lines represent environmental structure or unclaimed portions of the riding device and do not form a portion of the claimed design.

1 Claim, 8 Drawing Sheets---
